UNITED STATES PATENT OFFICE.

MORITZ WEBER, OF ST. LOUIS, MISSOURI, ASSIGNOR TO ST. LOUIS CAR COMPANY, OF ST. LOUIS, MISSOURI, A CORPORATION OF MISSOURI.

FOLDING CAR-STEP.

SPECIFICATION forming part of Letters Patent No. 689,629, dated December 24, 1901.

Application filed May 10, 1901. Serial No. 59,618. (No model.)

To all whom it may concern:

Be it known that I, MORITZ WEBER, a citizen of the United States, residing in the city of St. Louis, in the State of Missouri, have invented certain new and useful Improvements in Folding Car-Steps, of which the following is a full, clear, and exact description, reference being had to the accompanying drawings, forming part of this specification.

10 My invention relates to that class of steps used upon cars having vestibules intermediate of the ends thereof, the object of the invention being to provide a construction whereby the upper members of the steps may be moved upwardly into alignment with the floor of the vestibule when the door at one side of said vestibule is closed and the set of steps thereat is not in use.

20 My invention consists in features of novelty hereinafter fully described, and pointed out in the claims.

Figure I is a view in elevation showing my improved steps. Fig. II is a vertical sectional view taken on line II II, Fig. I. Fig. 25 III is an enlarged detail sectional view taken on line III III, Fig. I. Fig. IV is an enlarged perspective view of one of the hinge members applied to the ends of the upper folding riser. Fig. V is an enlarged perspective view 30 of one of the hinge members applied to the ends of the upper folding step. Fig. VI is a view in rear elevation looking at the steps at the location of the locking appliance. Fig. VII is a perspective view of a form of implement used for manipulating the step-locking 35 appliance.

1 designates the side walls of a car to which my steps are shown applied, and 2 is the vestibule-floor, supported by sills such as shown 40 at 3, Fig. II.

4 designates benches suspended from the lower body, and 5 and 6 are respectively the lower steps and risers stationarily held to the benches.

45 7 designates a pair of hinges, one leaf of each of which is secured to the sill 3, while the other leaf of each hinge is secured to a folding riser 8, that is upheld by said hinges immediately beneath the edge of the vestibule floor 2 and adapted to be swung upwardly into line with said floor.

9 designates a foldable step swingingly connected to the folding riser 8, adapted to rest on the uppermost stationary riser 6 and also capable of being moved upwardly into line 55 with the vestibule-floor 2. The step 9 is joined to the folding riser 8 by a pair of hinge members 10, secured to the ends of said step 9, and pivotally connected to hinge members 11, that are secured to the ends of the risers 60 8. In each hinge member 11 is an aperture 12. (See Fig. IV.)

Seated in the benches 4 are sockets 13.

14 and 16 designate a pair of throw-bars that are provided, respectively, with reduced 65 outer ends 15 and 17, slidably positioned in the apertures 12 of the hinge members 11 and adapted to enter the sockets 13 in the benches 4 when the throw-bars are moved outwardly at the time that the steps are in the lowered 70 position seen in Figs. I, II, and VI. The inner ends of the throw-bars 14 and 16 are connected by a rocking link 18, pivoted at its ends to said throw-bars and mounted upon a central pivot 19, carried by a pivot-plate 20, 75 that is secured to the folding riser 8. The folding riser 8 contains an opening located beside the pivot-plate 20. Seated in the opening in said riser is a frame 21, containing a 80 recess 22 and a slot 23.

24 designates an ear connected to the throw-bar 16 by bolts 25 or other suitable means of attachment.

26 designates a handle, preferably of U shape, having its arms connected to the ear 85 24 by a pivot-pin 27. The handle 26 is designed to lie in the recess 22 of the frame 21 when the throw-bars 14 and 16 are projected outwardly, and while in such position the handle prevents longitudinal movement of the 90 throw-bars, and therefore provides for the retention of the ends 15 and 17 of said bars in the sockets 13 and obviates liability of the bars being disconnected from the benches 4 when they have been thrown into engagement 95 therewith by being carried into said sockets.

When it is desired to close the door of the vestibule at either side of the car, the handle 26 is moved out of the recess 22 in the frame 21 and moved longitudinally in the slot 23, 100 contained by said frame, thereby carrying the throw-bar 16 inwardly and releasing its

outer end from engagement in the socket 13, in which it was seated. On the inward movement of the throw-bar 16 the rocking link 18 is moved on its pivot; and the throw-bar 14 is drawn inwardly simultaneously with the throw-bar 16, so as to free it from the socket with which it was engaged. The folding riser 8 and foldable step 9 may then be elevated into line with the vestibule-floor 2, as shown by 10 dotted lines in Fig. II, when the legs 10^a and 11^a of the hinge members 10 and 11 will abut against each other, the legs 11^a serving as braces for the legs 10^a to support the step 9. The riser 8 is sustained in elevated position by moving the throw-bars 14 and 16 outwardly into engagement with sockets 28, mounted on the inner faces of the benches 4, as seen in Fig. II.

In order to provide for the convenient manipulation of the handle 26, I make use of the implement shown in Fig. VII, which consists of lever having a handle 29 and a shank 30, provided with a pivoted stud 31. In the use of this implement the end of the shank 25 is placed between the arms of the handle 26, and being slipped back of said handle the handle is pried outwardly to move it into horizontal position in alignment with the slot 23 in the frame 21. The pivot-stud 31 of the implement 30 is then placed in the socket-plate 32, mounted on the riser 8, (see Fig. I,) and upon the implement being rocked on its pivot the handle is carried longitudinally in the slot 23, and the throw-bars 14 and 16 disengage from the 35 sockets 13. Then upon the lever 29 of the implement being depressed the implement is carried to the floor 2 of the vestibule, and the riser 8 and step 9 are raised into line with the vestibule-floor. The implement is then swung 40 laterally and the throw-bars are moved into engagement with the sockets 28, so that they will support the elevated riser and step.

I claim as my invention—

1. The combination with a floor of a car, of 45 a riser swingingly supported beneath said floor, and a step hinged to said riser, said riser

and step being adapted to be moved upwards into alignment with said floor, substantially as described.

2. The combination with a floor of a car, of 50 a riser swingingly supported beneath said floor, a step hinged to said riser and means for retaining said riser and step in lowered position, or in a horizontal position in line with said floor, substantially as described. 55

3. In a folding car-step, the combination of a riser hinged to a floor of a car, a step hinged to said riser, and a pair of throw-bars carried by said riser, said throw-bars being arranged for engagement with a fixed member carried 60 by the car, whereby said riser and step may be maintained in a lowered position, or in a position in alignment with said floor, substantially as described.

4. In a structure of the class described, the 65 combination with a car body and floor, of a pair of benches, one or more stationary steps mounted on said benches, a folding riser swingingly supported beneath said floor, a foldable step hinged to said riser, a pair of 70 throw-bars carried by said riser, and sockets seated in said benches adapted to receive said throw-bars when said riser and foldable step are in lowered position or in alignment with said door, substantially as described. 75

5. In a structure of the class described, the combination with a car body and floor, of a pair of benches, one or more steps stationarily supported by said benches, a riser hinged to said floor, a foldable step hinged to said riser, 80 a pair of throw-bars carried by said riser and adapted for engagement in sockets seated in said benches, a slotted frame mounted in said riser, an ear carried by one of said throw-bars and arranged to operate in said frame and a 85 handle connected to said ear whereby said throw-bars may be moved longitudinally, substantially as and for the purpose set forth.

MORITZ WEBER.

In presence of—

GEO. KOBRESCH,
H. F. VOGEL.
